ESTA W. RANCK, OF CENTRAL AGUIRRE, PUERTO RICO

MASONRY WALL AND WALL UNIT

Application filed January 27, 1931. Serial No. 511,630.

My invention relates to an improved masonry wall construction and a novel unit or building block used in constructing the same.

Up to the present time most concrete walls have been of two general types, the first being a solid reinforced wall made of poured concrete and the second type being made up of blocks, tile or other masonry units, superposed and with a layer of mortar therebetween much in the same manner as the ordinary brick wall.

The solid reinforced wall has the advantage of great tensile strength enabling the wall to resist bending strains, shocks and uneven settling of the foundation. This type of wall, however, has the disadvantage that it is expensive in the use of material since the concrete near the center of the wall performs much less useful work than that at the outer edges. The high cost of the solid wall is also increased due to the necessity of providing building forms and of picking the surfaces of the wall to provide a binding surface for mortar or stucco. It is also difficult to properly cure vertical solid concrete walls. They do not provide good insulation and they tend to promote dampness wherever used.

The second type of wall, made up of hollow blocks, tile or other units is more economical in the use of materials, requires no forms, provides better insulation and requires less time to construct. The building units can be made by machine and properly cured before being placed in the wall. This type of wall, however, has a disadvantage that no practical scheme or design has been developed to make it possible to properly reinforce such a wall both vertically and horizontally. These walls are therefore lacking in tensile strength and do not present a high resistance to building strains, shocks and uneven settling of the foundation. These walls are furthermore quite expensive to build due to the fact that skilled labor must be employed to properly lay the blocks with a uniform layer of mortar separating the respective units.

It is an object of the present invention to combine in a new type of masonry unit and a wall constructed therefrom, the advantages

of both the solid reinforced concrete wall and the hollow block wall and to eliminate the disadvantages of each.

It is a further object to provide a building unit which when incorporated in a wall will provide continuous communicating passages between adjacent blocks for the reception of reinforcing bars, wiring conduits, and the like and for the reception of concrete, mortar or other cementing material so as to form a horizontal and vertical reinforced wall having a large percentage of its volume made up of dead air spaces.

A further object of the invention is to provide a unit which may be incorporated in a wall by un-skilled labor, which may be readily and correctly positioned in the wall and which when so positioned will automatically form with adjacent units, the passages above referred to and also the dead air spaces.

A still further object of the invention is to provide a building unit, contrary to the common practice, which is not intended to extend entirely through the wall from one side to the other but extends only half way through the wall, forming a portion of one face of the wall while a similar unit, placed back to back with the first unit, forms a similar portion of the opposite face of the wall and one in which the dead air space is not formed in the units themselves, but is incorporated between the concave backs of two units when they are fitted together.

A wall constructed according to my invention has the strength and the freedom from cracking of a solid reinforced concrete wall, which, it in fact is. It may be constructed at a low cost with a saving of approximately fifty percent in materials over a solid wall, no forms or skilled labor is required to build the wall, there is no necessity of picking or roughening the surface of the wall after building as the faces of the units may be properly finished during manufacture.

Further objects and advantages not specifically mentioned will become apparent during the course of the following detailed description taken in conjunction with the 100

accompanying drawings which form a part of this specification, and in which:

Figure 1 is a perspective view of a portion of a wall and floor constructed according to my invention;

Fig. 2 is a perspective view showing the construction of the back face and bottom edge of one of the units;

Fig. 3 is a view illustrating a corner unit;

Fig. 4 is a vertical transverse cross section through the wall between two units;

Fig. 5 is a vertical transverse cross section of the wall taken on a line passing through the superposed units;

Fig. 6 is a horizontal cross section of the wall taken on the line 6—6 of Fig. 4;

Fig. 7 is a vertical central cross section taken on the line 7—7 of Fig. 5;

Fig. 8 is a detail cross section of the floor shown in Fig. 1; and

Fig. 9 is a perspective view of a modified unit.

Referring now to the drawings in detail and more particularly to the individual units used in constructing my improved wall, 10 indicates the block or unit proper, the main body of which is composed of a comparatively thin rectangular slab 11. Formed integrally with the body portion 11 and on the back thereof is a continuous flange or rim 12 which is disposed approximately at right angles to the rear face of the slab 11 and which forms with said slab a recess 13.

The flange or rim 12 is spaced from the edges of the block at the top and sides thereof but may be formed flush with the bottom edge as clearly shown. By so spacing the flange or rim from the edge of the block, a recess 14 is formed at the top of the block and a recess 15 is formed at each side of the block. A longitudinal V-shaped rib 16 is formed on the under face of the flange 12, which as before stated is flush with the bottom edge of the slab 11.

My invention also contemplates an improved wall structure employing the units above described. The preferred method of building such a wall would be to first construct a suitable foundation of concrete or other masonry work which should have embodied therein vertical reinforcing rods of steel or the like, spaced apart approximately the width of one of my improved units. These reinforcing rods should have their lower ends embedded in the foundation and they may extend vertically the full height of the wall.

The first course of the units may then be set up on the foundation in mortar or plastic concrete. The units are set up in pairs, back to back with the rims of the flanges 12 in contact and with the faces 11 of the units forming the opposite faces of the wall. It will be noted that two units in effect form a block and that the recesses 13 combine to form a

dead air space 13a. The second block or pair of units is laid along side of the first pair with the vertical edges thereof contacting directly with the vertical edges of the adjacent pair of units. When the pairs of units are laid in abutting relationship the recesses 15 combine to produce a vertical well or column form 17 with the vertical reinforcing members 18 enclosed therein. This vertical well or space is then filled with concrete or other plastic material and since each succeeding course of blocks provides similar spaces which register with those of the first course they form reinforced concrete columns when filled. It will be noted then that the abutting ends of adjacent pairs of units serve as forms for these vertical reinforced concrete columns when filled. It will be noted then that the abutting ends of adjacent pairs of units serve as forms for these vertical reinforced concrete columns which are bonded fast to the units, forming in effect a monolithic wall provided with a plurality of dead air spaces.

The recesses 14 in the top of each unit combine, when the units are assembled, in pairs to produce a horizontal and longitudinally extending continuous trough or channel 19 which extends the full length of the wall.

The flanges or rims 12 may be so formed that the channel 19 will be deeper near its outer edges than in the center where the rims of the two units contact with each other. When the second course of units is to be laid on top of the first course, the trough or channel 19 is partially filled with concrete or mortar and the horizontal reinforcing bars 20 are placed in the trough. The trough is then filled with concrete or mortar, the same being leveled off even with the top of the units with a straight-edge or other suitable tool. Another course of blocks is then set upon the blocks just described while the concrete in the trough 19 is still sufficiently soft for the rib 16 to penetrate the same and compact it. It will be noted here also that the edges of the blocks composed of the pairs of units are in direct contact without any layer of mortar whatever between the same. It will also be noted that the concrete in the trough 19 which is compacted by the rib 16 forms a horizontal reinforced concrete column or girder which will be integrally united with the vertical columns and with the adjacent blocks to form a truly monolithic wall. The ribs 16 being embedded in the concrete in the trough 19 producing an impervious labyrinth joint which also aids in preventing displacement of the individual blocks or units. The edges of the body 11 of the units 10 may be beveled off as at 11a so that when the units are embodied in the wall a V-shaped recess will be formed in the joint which may, if desired, be pointed up with a special concrete mix or

may be left hollow to impart a suggestion of thickness to the block.

The above described procedure for laying the first two courses is continued until the wall has reached the desired height. It will be noted that in the finished wall, the vertical and horizontal concrete columns and girders form in effect a one-piece lattice work, with the blocks, made up of pairs of units, forming the mold for said one-piece lattice work and also filling the spaces between the concrete columns and girders and being integrally bonded thereto. It will also be noted that a large dead air space is also enclosed between each pair of units 10.

Half or fractional units may be used around door and window frames when necessary and a corner unit 21, shown in Fig. 2, may be employed to finish the corners of the wall. The inner face of the corner unit 21 is also hollowed out to form a recess 22 which combines with the pivotal recess 15 of the pairs of units of each wall to produce a form for the corner column of the building.

Referring now to Fig. 8, when my improved units are employed in constructing a floor or roof, a number of units 10 are supported in correct position with the flanges 12 extending upwardly. A slightly modified unit 23 is then employed to complete the other half of the thickness of the roof or floor. This modified unit 23 is also formed with a slab-like main body 24 and is provided with a marginal flange 25 enclosing a recess 26. The flange 25 is of the same dimensions as the flange 12 of the unit 10 so that the units 10 and 23 are placed back to back and the flanges will register to produce a closed dead air space 27. It will be noted that the units 23 are slightly smaller in surface dimensions than the units 10 so that they will combine with the units 10 when employed in constructing a floor or roof, to produce longitudinally and transversely extending channels or troughs 28 which are filled with concrete or mortar, forming with the pairs of blocks 10 and 23 a monolithic structure. Reinforcing bars or rods 29 may be embodied in the concrete in the troughs 28 to further strengthen the structure.

If it becomes desirable to build a wall thicker than that produced by a pair of units 10, one or more units 23 may be sandwiched between the outer units 10 to produce a wall of any desired thickness. It will be noted that if this is done, an increasingly greater number of dead air spaces will be formed due to the fact that each block 23 will produce another dead air space.

If it is desired to provide a wall with staggered joints, a double unit can be produced such as shown in Fig. 9. This double unit 30 would be a duplicate of two units 10 placed end to end. The unit would be composed of a flat slab-like portion 31, forming the main

body of the unit and would be provided with two continuous flanges or rims 32 and 33, the bottom of the same being provided with ribs 34 corresponding to the rib 16 on the unit 10. A channel 35 would be formed between the flanges 32 and 33 and vertical recesses 36 would be formed at each end of said unit as well as a recess 37 at the top thereof. The recesses 36 and 37 would correspond to the recesses 15 and 14 respectively, of the unit 10.

It will thus be seen that I have provided a novel block and wall constructed therefrom which has the strength of a reinforced concrete wall and the economy and insulating qualities of an insulated block wall. The horizontal troughs and vertical column spaces formed between the blocks provide ideal passage ways in which to place piping and wiring which has always been a difficult problem in existing block walls.

Although a preferred embodiment of the invention has been shown and described, it will be understood that various changes in the details of construction may be made without departing from the spirit of the invention as defined by the appended claims.

I claim:

1. A building unit comprising a rectangular body, a continuous flange formed with said body and extending outwardly from the back thereof, said flange being spaced inwardly from the top and side edges of said body and disposed substantially flush with the bottom edge thereof, and a projection extending from the side of said flange which is flush with said bottom edge of said body.

2. A building block composed of a pair of units, each unit comprising a rectangular body, a continuous flange extending from the rear face thereof spaced from the side and top edges of said body and flush with the bottom edge thereof whereby when said units are placed back to back to form said building block, the edges of said flanges will contact to enclose a dead air space within said block and whereby vertical and horizontal troughs will be formed at the sides and top of said block due to said spacing of said flanges, and a depending projection formed with the portion of said flange which is flush with the bottom edge of each unit.

3. In a hollow block wall, a block comprising a pair of similar units arranged back to back and having their forward faces forming a portion of the surfaces of said wall, a recess formed in the rear face of each unit whereby to form a dead air space when said units are placed back to back in a wall, said units having a channel formed in the side and top edges thereof whereby to produce intercommunicating longitudinally and vertically extending passages when said units are assembled in said wall, a binder adapted to fill said passages and reinforcing bars embedded in the binder in said passages whereby to form

reinforced vertical columns and girders with said units united thereto and producing in effect a reinforced monolithic wall having dead air spaces enclosed therein.

5 4. In a hollow block wall, a block comprising a pair of similar units arranged back to back and having their forward faces forming a portion of the surfaces of said wall, a recess formed in the rear face of each unit whereby to form a dead air space when said
10 units are placed back to back in a wall, said units having a channel formed in the side and top edges thereof whereby to produce inter-communicating longitudinally and vertically extending passages when said units are assembled in said wall, a longitudinally extending rib formed with the bottom edge of each of said units, and a binder adapted to fill said passages and form with said units a virtually monolithic wall.
